[73] Assignee: **Thrall Car Manufacturing Company**, Chicago Heights, Ill.

[57] **CLAIM**

The ornamental design for a railroad hopper car end slope collar casting, as shown and described.

[**] Term: 14 Years

DESCRIPTION

[21] Appl. No.: 157,314

FIG. 1 is a front elevational view of our new design of railroad hopper car end slope collar casting;
FIG. 2 is a rear elevational view thereof;
FIG. 3 is a side elevational view thereof, it being understood that the opposite side is a mirror image of that shown;
FIG. 4 is a sectional view thereof along the line 4—4 of FIG. 1;
FIG. 5 is a top plan view thereof; and
FIG. 6 is a bottom plan view thereof.
